The ornamental design for a football tee, as shown and described.

DESCRIPTION

FIG. 1 shows a perspective view of a first embodiment of my claimed design.

FIG. 2 shows a top view of my claimed design.

FIG. 3 shows a right side view of my claimed design, the left side view being a mirror image thereof;

FIG. 4 shows a front view of my claimed design.

FIG. 5 shows a rear view of my claimed design.

FIG. 6 shows a bottom view of my claimed design.

FIG. 7 shows a perspective view of a second embodiment of my claimed design, wherein the side, front, rear and bottom views are the same as in the first embodiment; and,

FIG. 8 shows a top view of the second embodiment of my claimed design.

The difference between the embodiment of FIGS. 1 and 2 on the one hand, and the embodiment of FIGS. 7 and 8 on the other hand is as follows: With reference to FIG. 2, the lower recess has a scalloped surface surrounding an opening with the scalloped surface including a plurality of apices consisting of arcuate lines.
